UNITED STATES PATENT OFFICE.

WILLIAM E. DUNBAR, OF JACKSONVILLE, FLORIDA.

SWIVEL BRACKET.

Application filed October 27, 1922. Serial No. 597,347.

To all whom it may concern:

Be it known that I, WILLIAM E. DUNBAR, a citizen of the United States, residing at Jacksonville, in the county of Duval and 5 State of Florida, have invented new and useful Improvements in Swivel Brackets, of which the following is a specification.

This invention relates to supporting brackets for use in holding maps, blue prints, pictures and in fact many articles in upright position and in such a manner that the various separate articles may be swung or turned to permit examination thereof and of the underlying objects.

15 An important object is the provision of a device of this character which includes supports adapted to be mounted upon a wall or the like and with which are pivotally connected links with which are in turn 20 pivotally connected arms which carry the supports for the maps, blue prints, pictures or the like, a plurality of these units being provided and all being similar.

An additional object is the provision of a 25 device of this character which will be simple and inexpensive in manufacture, easy to install, efficient and durable in use and a general improvement in the art.

With the above and other objects and advantages in view the invention consists in the details of construction to be hereinafter more fully described and claimed and illustrated in the accompanying drawings, in which:

35 Figure 1 is a side elevation illustrating my invention,

Figure 2 is a plan view,

Figure 3 is a perspective view of the stationary leaf.

40 Referring more particularly to the drawings the letter A designates an upright support which might be a wall, post or the like and upon which my device is mounted.

In carrying out my invention I provide 45 hinge leaves 10 provided with holes 11 for the passage of securing means by virtue of which they may be secured to the wall or post A. Each hinge leaf is formed with spaced knuckles 12 through which passes a removable pintle pin 13. Associated with 50 each hinge leaf is a link 14 provided with a series of similar vertically extending trans-

verse holes 15, one endmost hole being designed for the passage of a pintle pin 13 whereby the link will be pivotally mounted 55 with respect to the hinge leaf. The numeral 16 designates a preferably rectangular sheet of material which may be of wood, fiber, wall board or the like and upon which may be suitably mounted a map, blue print, picture or other object to be exhibited. Each sheet 16 has secured thereto two or more transverse bars or strips 17 which project beyond one edge and which are formed with depending trunnions 18. It is intended that 60 a plurality of these members 16 be used and that the trunnions 18 be engaged within the successive holes 15 in the links 14.

Assuming that the device has been constructed and assembled as above described 70 it will be apparent that all the members 16 are freely rotatable with respect to the members 14 and that the links 14 are capable of swinging movement upon the pintle pins 13. In this way it will be seen that the various 75 members 16 may be quickly and easily swung with respect to one another and with respect to the wall A whereby to permit ready inspection or examination of the objects carried by the sheets 16.

80 While I have shown and described the preferred embodiment of the invention it is of course to be understood that I reserve the right to make such changes in the form, construction and arrangement of parts as 85 will not depart from the spirit of the invention or the scope of the subjoined claim.

Having thus described my invention I 90 claim:

A device of the character described comprising a series of hinge leaves formed with knuckles and designed to be mounted upon an upright supporting surface, pintle pins passing through the knuckles of each leaf, a link for each leaf provided with a plurality 95 of spaced vertical holes, one endmost hole being designed for the reception of the pintle pin, and a supporting sheet carrying arms formed with depending trunnions rotatably engaged within other holes of the links, the 100 links being adapted to carry a plurality of sheets.

In testimony whereof I affix my signature.

WILLIAM E. DUNBAR.
